UNITED STATES PATENT OFFICE

PAUL M. WEAMER, OF GLADWYNE, PENNSYLVANIA, ASSIGNOR TO LEE RUBBER & TIRE CORPORATION, OF CONSHOHOCKEN, PENNSYLVANIA, A CORPORATION OF NEW YORK

DESIGN FOR A TOY FIGURE

Application filed December 27, 1929. Serial No. 33,954. Term of patent 3½ years.

To all whom it may concern:

Be it known that I, PAUL M. WEAMER, a citizen of the United States, residing at Gladwyne, in the county of Montgomery and State of Pennsylvania, have invented a new, original, and ornamental Design for a Toy Figure, of which the following is a specification, reference being made to the accompanying drawings, forming a part thereof.

Of the accompanying drawings, Fig. 1 is a front elevation showing a toy figure embodying my new design.

Fig. 2 is an edge view thereof.

I claim:

The ornamental design for a toy figure as shown.

PAUL M. WEAMER.
